United States Patent

Des. 241,034
Patented Aug. 17, 1976

241,034

TELEPHONE PLUG OR SIMILAR ARTICLE

Paul V. De Luca, Port Washington, N.Y., assignor to
Porta Systems, Syosset, N.Y.

Filed Oct. 23, 1974, Ser. No. 517,099

Term of patent 14 years

Int. Cl. D13—03

U.S. Cl. D26—1 A

FIG. 1

FIG. 4

FIG. 2

FIG. 3

FIG. 5

FIG. 6

FIG. 1 is a front elevational view of a telephone plug or similar article showing my new design;

FIG. 2 is a rear elevational view thereof;

FIG. 3 is a side elevational view thereof;

FIG. 4 is a side elevational view thereof, showing the side opposite that seen in FIG. 3;

FIG. 5 is a top plan view thereof; and

FIG. 6 is a bottom plan view thereof.

I claim:

The ornamental design for a telephone plug or similar article, substantially as shown.
